UNITED STATES PATENT OFFICE.

CHARLES AMOS HODGE, OF KNOXVILLE, TENNESSEE.

IMPROVEMENT IN PISTON-PACKINGS.

Specification forming part of Letters Patent No. **142,914**, dated September 16, 1873; application filed July 29, 1873.

To all whom it may concern:

Be it known that I, CHARLES AMOS HODGE, of Knoxville, in the county of Knox and in the State of Tennessee, have invented certain new and useful Improvements in Piston-Packings; and do hereby declare that the following is a full, clear, and exact description thereof, reference being had to the accompanying drawings and to the letters of reference marked thereon, making a part of this specification.

The nature of my invention consists in the construction and arrangement of a piston-packing, as will be hereinafter more fully set forth.

In order to enable others skilled in the art to which my invention appertains to make and use the same, I will now proceed to describe its construction and operation, referring to the annexed drawings, in which—

Figure 1 is a side view of my piston, part in section. Fig. 2 is a longitudinal section of the same, and Fig. 3 is a perspective view of the packing-rings.

A represents a solid ring, which slides on the arms or lugs B B of the piston, which ring is turned about one and three-quarter inch smaller than the diameter of the cylinder. Around the ring A is placed an eccentric ring, C, which operates as a spring, and at the same time carries the packing true and keeps the piston in the center of the cylinder by having one side of said ring turned one-eighth of an inch thicker than the other. D D represent the outside or packing rings, which come to the face of the cylinder, and are about half an inch thick. These are turned, by a larger spring, into the cylinder. The eccentric ring C, acting as a spring, carries the

packing-rings true, and keeps the piston in the center of the cylinder. When the packing-rings D D wear down or get small, so as to cause the engine to blow, a liner is placed inside of the outside rings D D, and on the outside of the eccentric ring C, which decreases the size of the said eccentric ring, it being an open ring, or causes it to spring down and force the liner against the outside rings D D. This stops the engine from blowing and brings the piston back to the center of the cylinder, where it was originally. The outside or packing rings D D are made open, and doweled by means of a dowel, a, of any suitable construction, so that they can turn on the eccentric or spring ring C, and not allow the openings to come together, which would cause the steam to blow through from one end of the cylinder to the other. E represents the piston-rod, and G G the heads secured to the arms B B, as shown.

Having thus fully described my invention, what I claim as new, and desire to secure by Letters Patent, is—

The combination, with the shaft E and arms B B, of the solid ring A, eccentric or spring ring C, and the outside or packing rings D D, with dowels a, all substantially as and for the purposes herein set forth.

In testimony that I claim the foregoing I have hereunto set my hand this 16th day of July, 1873.

C. A. HODGE.
